UNITED STATES PATENT OFFICE

2,430,183

DOUBLE ROTATION ELASTIC FLUID TURBINE

Ragnar Olov Jacob Möller, Finspong, Sweden

Application November 15, 1945, Serial No. 628,682
In Sweden December 16, 1944

6 Claims. (Cl. 253—16.5)

1

This invention relates to double rotation elastic fluid turbines of the radial or axial flow type, and more particularly to turbines of said class which are provided with an auxiliary impulse blade system adapted to convert, at a high efficiency, the highest pressure stage into work. An example of the turbine of this class is described in the British Patent No. 570,624 where it is disclosed as a driving mechanism for vessels, especially torpedoes. For such purposes the double rotation reaction type of turbine is a preferred driving motor, as the torques of the oppositely moving turbine rotors are equal to each other, so that the reaction moments may balance each other. If, however, as the case may be in respect of the driving mechanism disclosed in said patent, the double rotation reaction type of turbine is provided with an auxiliary set of impulse turbine blades, reaction forces are produced in the stationary expansion nozzles belonging to the impulse blade system which produce torques appearing as a tendency of the torpedo body to heel over. In case of torpedoes it is, however, of great importance to avoid heeling over.

The object of this invention is to suppress to the largest extent possible the heeling over tendency and, should a heeling over nevertheless occur, to restore the normal state of balance.

In order to avoid the formation of torques, that may give rise to heeling over, the auxiliary impulse blade system according to a feature of this invention is provided with two axially spaced sets of stationary expansion nozzles with the nozzles of one set directed oppositely to those of the other set as far as the peripheral direction is concerned. By this means the reaction forces as produced in the expansion nozzles of one set may be balanced by the oppositely directed reaction forces produced in the nozzles of the other set.

According to a further feature of the invention means are provided to restore the equilibrium of the vessel if in spite of the above said arrangement of the expansion nozzles a heeling over should appear. To this end a member unaffected by the heeling over movement is provided which is adapted to control, either directly or by means of a servomotor, the distribution of the driving fluid to the expansion nozzles of the impulse blade system so that the counter-acting reaction forces above referred to become different in such a way that the prevailing reaction may restore the vessel to its normal position.

2

In the accompanying drawings a form of the invention is illustrated. Fig. 1 is an axial section of a portion of a torpedo turbine according to the invention. Fig. 2 is an axial section on a larger scale of an impulse section of a somewhat modified structure. Fig. 3 is a cross section on the line III—III of Fig. 2 of a portion or one group of expansion nozzles. Fig. 4 is an axial section of an impulse section of another modified form. Figs. 5—7 illustrate a control mechanism according to the invention. Fig. 5 is a section on the line V—V of Fig. 6, and Fig. 6 is a section on the line VI—VI of Fig. 5 and Fig. 7. The quadrant *k* of Fig. 6 represents a section on the line *k*—*k* of Fig. 5. Fig. 7 shows a portion of the groups of nozzles shown in Fig. 6, as seen from above. Fig. 8 shows a modified form of this portion.

With reference to Fig. 1, the numeral 1 designates the body of the vessel, which may be assumed to be a torpedo, 2 is the turbine casing, 3 is one turbine shaft and 4 the other turbine shaft. Shaft 4 is concentrically surrounded by the tubular shaft 3 and may itself be tubular, as shown. Shafts 3 and 4 may represent the propeller shafts of the torpedo or shafts coupled thereto. 5 is a turbine disc supported by the other shaft 3, and 6 is a turbine disc supported by the inner shaft 4. The turbine discs 5 and 6 carry the oppositely rotating blades of the radial flow reaction system 7. Formed in the wall of shaft 4 in register with the blade system 7 are ports 8 to allow the driving fluid to enter the shaft 4 that serves as a distance pipe. Connected to the turbine disc 5 by means of a drum-like wall 9 is an inwardly extending turbine disc 10 which carries in conjunction with the opposite surface of turbine disc 6 a set of impulse blades 11¹—11³ for double rotation. In addition, discs 6 and 10 carry reaction blades 20, 21 situated on a larger radius than said impulse blades. Inserted between the turbine disc 10 and a radially extending wall 12 of the turbine casing is a labyrinth packing 13. Provided inside the impulse blade system are two annular sets of expansion nozzles 14, 15 adapted to admit the driving fluid to the impulse blades from a central passage 16.

The innermost impulse blade ring 11¹ situated next to said nozzles which is attached to the turbine disc 6 is adapted to be impelled by the driving fluid admitted from the set of nozzles 14 only, whereas the second impulse blade ring 11² which is carried by the turbine disc 10 comprises two axially spaced sets of blades, one of

which is adapted to be directly impelled by the fluid admitted from the set of nozzles 15, while its other set of blades is adapted to be operated by the fluid discharged from the first blade ring 111.

The orifices of the nozzles are oppositely directed so as to agree with the opposite directions of rotation of the blade rings directly impelled by the fluid when leaving the nozzles. The reaction forces emanating from the expansion nozzles become therefore oppositely directed and, since they are equal, they may balance each other.

Since part of the driving fluid as delivered by the nozzles acts directly on the second blade ring 112, an increased amount of power may be yielded by this blade ring. By this means a power balance may be obtained within the impulse blade system proper which is not obtainable in conventional double rotation impulse turbines having but one passage for the driving fluid, in which the rotor half to which the blade ring first impelled by the driving fluid belongs, receives and delivers more power than the other half of the rotor. In certain kinds of turbines, especially those adapted to drive electric dynamos, it may be desired to distribute the power in some appropriate way and this may be done by means of an impulse turbine modified as above described.

In Fig. 2 is shown an impulse turbine in which the driving fluid is supplied at the outer periphery of the turbine to then pass inwardly, the design being for the rest similar to that above described. The reference numerals 14 and 15 designate as before two annular expansion nozzles and 16 is the common fluid supply passage therefor. 6 and 10 are the two oppositely rotating turbine discs carrying the impulse blades. The innermost impulse blade ring 111 comprises a single set of blades situated right opposite the nozzle ring 14, whereas each of the remaining blade rings 112 and 113 is provided with two sets of blades, separated by a partition 17 and each situated right opposite an individual one of the nozzle rings 14 and 15. If desired, the partition 17 may be dispensed with.

Fig. 3 shows the position of guide blades 14a and 15a provided in the nozzle rings to divide each of them into a plurality of separate orifices. As shown, the direction of the orifices of one nozzle cross the direction of those of the other nozzle under very obtuse angles looking from the inside or the outside of the nozzle rings, so that the fluid will leave the two nozzle sets in nearly tangential, opposed directions.

As shown in Figs. 1 and 2, there may be a comparatively wide radial gap between the nozzle ring 15 and the second blade ring 112. The width of this gap may be reduced so as to agree with the width of the radial space between each two adjacent blade rings by placing the set of nozzles 15 nearer to said second blade ring, as illustrated in Fig. 4. Here, the same reference numerals are used as in Fig. 2. Another way in which to obtain the same effect is to increase the radial thickness of the second blade ring 112 right opposite the nozzle ring 15.

In the structures above described with reference to Figs. 1-3, those reaction forces which emanate from one nozzle ring will be balanced by those emanating from the other nozzle ring. In the embodiment shown in Fig. 4 the balancing effect is not equally perfect owing to the placing of the two nozzle rings on different radii. Evidently, a

certain tendency towards heeling over cannot be avoided in this case.

In order to avoid any tendency towards heeling over that may appear from the one reason or the other, a member that cannot be affected by the heeling over movements may be provided which may either be constructed to act as a fluid distributor for the expansion nozzles or adapted to control such a distributor via a servo motor. 10 Figs. 5-7 illustrate an example of the said first mentioned arrangement and Fig. 8 illustrates a modification thereof.

Mounted on an edge 18 coinciding with the axis of the turbine is a pendulum 19 the lower free end of which forms a valve body 20, the operative surface of which is concentric with the turbine axis and situated in close proximity to the inner cylindrical surface of the nozzle rings. Below said valve surface the nozzles 14 and 15 15 are replaced by a solid ring segment 21 the profile of which looking from the centre of the turbine may be as shown in Fig. 7 or Fig. 8. In these illustrations the outline of the valve body is indicated by dotted lines, as shown at 20.

In Fig. 7 a steplike form of ring segment 21 is shown, the solid segments of the nozzle rings 14 and 15 being in staggered relation to each other, inasmuch as the solid segment of nozzle ring 14 is displaced to the left in relation to the solid segment of nozzle ring 15. In Fig. 8 the solid segments of the two nozzle rings are located in axial alinement. In the first mentioned case the profile of the valve body 20 is square-shaped, in the last-mentioned case steplike. In both cases 30 the valve body extends normally slightly over the nozzle ring 14 to the right of the solid segment 21 and to a corresponding extent over the nozzle ring 15 to the left of the solid segment 21. By 35 this means the reaction force emanating from one nozzle ring becomes equal to that emanating from the other nozzle ring. In case of a heeling over, for instance, to the right in the drawing, so that the solid segment 21 moves to the left in Figs. 7 and 8, the pendulum 19 due to its remaining in 40 vertical position will cover by its valve body 20 more orifices of the nozzle ring 14 to the right of the solid segment 21, while at the same time completely uncovering the nozzle ring 15 to the left of said segment. As a result, the admission 45 of driving fluid to the nozzle ring 14 will be reduced, allowing the reaction forces emanating from the nozzle ring 15 to preponderate over those emanating from the nozzle ring 14 and effect a turning of the casing of the turbine, corresponding in the example under consideration to 50 a heeling over to the left sufficient for restoring the normal equilibrium.

As already mentioned, the pendulum need not necessarily act as a valve, but may be arranged to 55 control a valve, as for instance, via a servomotor. The controlling device may, furthermore, be constructed so as to effect an increase (or decrease) of the impulse produced by the heeling over movement, for instance, so that a heeling over by one degree may effect a turning of the valve by several degrees or by a fraction of a degree only, according as it is desired to effect a more rapid or a more slow restoration of the normal position.

70 What I claim is:

1. A driving mechanism for vessels comprising in combination, a casing rigidly connected to the vessel, two rotatable driven elements, a reaction type of turbine having two oppositely rotatable main systems of reaction blades, each system

being drivingly connected to rotate one of the driven elements in an opposite direction from the direction of rotation of the other driven element, an auxiliary impulse blade system for converting the highest pressure stage into work, two oppositely directed annular sets of expansion nozzles rigidly connected to said casing for delivering driving fluid to said blade auxiliary system, an inlet positioned at the common axis of the driven elements for admitting driving fluid directly to said nozzles, means to direct the exhaust fluid from said auxiliary blade system to the main blade system, said nozzles being stationary with respect to the casing so that the oppositely acting turning moments resulting from the reaction forces produced in said sets of nozzles may balance each other for preventing heeling over of the casing and the vessel rigidly connected thereto.

2. A driving mechanism for vessels as claimed in claim 1, in which the impulse blade system comprises more than one blade ring, and in which the impulse blade ring situated next to the sets of expansion nozzles is arranged so as to be impelled by the fluid admitted from one of said sets of nozzles only, the next succeeding blade ring being arranged so as to be impelled, in part, directly by the fluid admitted from the other set of nozzles and, in part, by fluid that has already passed the said first-mentioned impulse blade ring.

3. A driving mechanism for vessels as claimed in claim 1, in which the impulse blade system comprises concentric blade rings and in which the innermost one of these blade rings is arranged to receive driving fluid from one set of nozzles only, while the blade ring next succeeding is arranged to be impelled, in part, directly by the fluid admitted from the other set of nozzles and, in part, by fluid that has already passed said first-mentioned impulse blade ring, said other set of expansion nozzles being displaced with relation to the first-mentioned set so as to extend nearly to the said last-mentioned blade ring.

4. A driving set for vessels as claimed in claim 1, in which the impulse blade system comprises concentric blade rings, and in which the innermost one of these blade rings is arranged to receive driving fluid from one set of nozzles only, while the blade ring next succeeding is arranged to be impelled, in part, directly by the fluid admitted from the other set of nozzles and, in part, by fluid that has already passed said first-mentioned impulse blade ring, said last-mentioned impulse blade ring, which is arranged to be directly impelled by the fluid delivered from said other set of expansion nozzles, being extended into close proximity to said set of nozzles.

5. A driving system for the propelling of vessels comprising in combination, a vessel, an elastic fluid turbine having a main system of reaction blades for rotating a propeller shaft in one direction, a casing stationary with respect to said vessel, another main system of reaction blades for rotating another propeller shaft in the opposite direction, an auxiliary impulse blade

system for converting the highest pressure stage of the driving fluid into work, two annular sets of expansion nozzles situated side by side for delivering driving fluid to said impulse blade system, the nozzles of the two sets being directed in opposite peripheral directions and being rigidly connected to the casing for allowing the oppositely acting turning moments resulting from the reaction forces produced in the two sets of nozzles to balance each other in order not to impart any turning tendency to the casing, and means responsive to heeling of the casing for controlling the admission of driving fluid through said sets of nozzles for maintaining the normal position of the casing with respect to its axis.

6. A driving mechanism for the propelling of vessels comprising in combination with the body of the vessel, an elastic fluid turbine of the double rotation type including a casing rigidly connected to said vessel and a pair of oppositely rotatable shafts, a main system of reaction blades for rotating a propeller shaft in one direction, another main system of reaction blades for rotating another propeller shaft in the opposite direction, and an auxiliary impulse blade system for converting the highest pressure stage of the driving fluid into work, two annular sets of expansion nozzles situated side by side for delivering driving fluid to said impulse blade system, the nozzles of the two sets being directed in opposite peripheral directions and being rigidly connected to the casing for allowing the oppositely acting turning moments resulting from the reaction forces produced in the two sets of nozzles to balance each other in order not to impart any turning tendency to the casing, and a valve mounted so as to be responsive to heeling of the turbine as a whole and the vessel body rigidly connected therewith about the axis of the turbine or another axis parallel thereto, which is adapted to cover and uncover parts of the sets of expansion nozzles under the action of a turning moment, in order thereby to adjust the distribution of driving fluid to both sets of nozzles with a view to restoring the normal position of the turbine and the vessel.
